UNITED STATES PATENT OFFICE.

ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY.

APPARATUS FOR USE IN THE MANUFACTURE OF BOOTS AND SHOES.

1,124,957.

Specification of Letters Patent.

Patented Jan. 12, 1915.

Application filed December 17, 1910, Serial No. 597,851. Renewed June 29, 1914. Serial No. 846,359.

To all whom it may concern:

Be it known that I, ARTHUR L. RUSSELL, a citizen of the United States, residing at Hyde Park, in the county of Norfolk and

5 State of Massachusetts, have invented certain Improvements in Apparatus for Use in the Manufacture of Boots and Shoes, of which the following description, in connection with the accompanying drawings, is a specification, like reference characters on the drawings indicating like parts in the several figures.

This invention relates to the manufacture of shoes and while there are disclosed 15 in this specification and drawings improvements in methods of making shoes, improvements in shoes and improvements in toe binders which respectively constitute the subjects matter of divisional applications 20 Ser. Nos. 711,648, 802,157 and 711,647, the invention herein to be protected relates more particularly to novel apparatus for use in the operations of lasting and temporarily securing shoe uppers.

25 A present general practice is to overwork the upper into lasted position about the toe end of the last by wipers that have acting edges shaped to embrace the toe portion of the shoe and lay the upper over the margin 30 of the innersole. The innersoles of welt and turn shoes are provided with upstanding lips or other formations that present a shoulder against which the upper is lasted. A binder of wire or other continuous material 35 is employed to secure the upper in lasted position by anchoring it at one end and drawing it tightly about the upper around the toe to bind it against the shoulder of the innersole after which it is anchored under tension.

An object of the present invention is to bind the toe without the use of anchor tacks and a further object is to improve the binding of the upper, which frequently slips to 45 some extent under the binding wire.

Other objects of the present invention are to provide means with which to improve the shaping of the upper to the last and the innersole and particularly the shaping of that 50 portion of the upper which overlies the margin of the shoe bottom, to increase the permanence of such shape for producing the shoe claimed in application Ser. No. 802,157,

and to provide improved means for applying binders and particularly for utilizing 55 the binder which forms the subject-matter of application Ser. No. 711,647.

The novel features of this invention, which include certain combinations of parts and more important details of construction, will 60 be better understood in connection with the following description of the apparatus and the manner in which it is contemplated it shall be used, and will then be pointed out 65 in the claims.

Figure 1 is a plan view of a machine equipped with the novel apparatus herein described and adapted for use in this invention; Fig. 2 is a perspective view of the binder; Fig. 3 is a detail of binder applying 70 devices; Fig. 4 shows the toe portion of a shoe having the upper secured by the binder of this invention.

The machine comprises the usual shoe supports at the heel 2 and toe 3 with heel 75 lasting wipers 4 and toe wipers 6. The latter are mounted on a vertically movable head 8 that is lifted by a foot treadle 10 and the wipers are opened and closed with a simultaneous longitudinal movement by cams 12 and link connections with a hand lever 15. These parts may all be as in the machine shown and described in United States Letters Patent No. 1,018,477, granted Feb. 27, 1912 on application of Matthias Brock. 80 In accordance with this present invention the toe wiper cams also support for movement toward and from operative relation to the shoe auxiliary devices 21 herein termed end rubbers that are pivoted on the 85 cams and have yielding edge members 20. These have a movement longitudinally of the shoe edge in rubbing contact with the sides of the toe.

In addition to their movement with the 95 toe wipers the end rubbers 21 have a rubbing movement directed toward the heel in contact with the upper, which creases the upper into the angle between the lip and the feather of a welt innersole. To this end 100 the end rubbers each have a crank arm 23 connected by an equalizer 24 to a slide that is guided in the cover plate of the wiper carrying head and is actuated by a lever 26 and a link connection to a lever 22 that is 105 pivoted on the same fulcrum as the wiper

operating lever 15 and overlies that lever. Lever 22 is slightly resilient and has a handle 27 and a stud by which it can be engaged with one or another of a segmental 5 row of holes in an enlargement of lever 15 whereby lever 22 and the end rubbers may be actuated with the wiper operating lever. The handle 27 also provides means for effecting independent turning movement of 10 the end rubbers. The end rubbers are eccentrically pivoted so that this independent movement by the handle 27 closes their yielding contact members 20 further, or with increased pressure, over the shoe bottom as 15 well as turning them in rubbing contact with the stock. It will be noted also that the normal movement of the end rubbers 21 with the wipers is accompanied by a rotation about their eccentric axis which advances or retracts them more rapidly than 20 the wipers are moved. Thus the end rubbers normally stand back of the wiper edges, in an out-of-the-way position, where they may not contact with the sides of the shoe in the 25 upward movement of the wipers along the sides of the shoe when the head is raised by the treadle 10. When the wipers advance to lay the upper over the feather of the innersole the end rubbers advance faster than the 30 wipers do, because of turning about their eccentric pivots, and so come into yielding pressing and rubbing contact with the upper against the lip of the innersole to crease it into the angle between the lip and the 35 feather. The end rubbers will be arranged to act on the shoe in the region of the tip seam where the upper materials are especially bulky and this creasing action is particularly desirable in order to obtain a 40 uniform position and appearance of the inseam and the welt in the welted shoe. This action of the end rubbers also effects a special tightening of the upper in the region of the tip seam and back of the ends of the 45 wipers where it serves to improve the lasting of the shoe. When the wipers are partially backed away from the overwiped upper to insert the binder the end rubbers are retracted faster and farther than the wipers 50 so that abundant space is made for placing the binder ends. As the wipers are advanced again the end rubbers are pressed against the ends of the binder and are turned rearwardly to draw rearwardly on 55 the binder strand. Additional rubbing by the devices 20, 21 can be effected by operating lever 22 alone by its handle 27. An adjusting nut 28 and spring 29 on the connecting link from lever 26 to lever 22 gives 60 opportunity for fine adjustment. The wipers and the end rubbers may be sufficiently heated by small gas flames at 25 below the plate 7 over which the wipers and end rubbers stand in their retracted position, said flames being particularly located 65

to heat the end rubbers. Any other heating means may of course be substituted.

The binder advantageously employed is a fabric or paper strip 30 with adhesive on the back that preferably is of a quality to be rendered tacky by heat. After the toe portion of the upper has been overwiped against the shoulder 32 of the innersole the wipers are backed away from the upstanding flange 34 of the upper far enough to allow the strip of binding material to be dropped edgewise between the wiper edges and the upper with its coated back toward the upper which has been warmed by previous contact with the heated wipers. The wipers are now again advanced to press the binder against the flange 34, and particularly against the base of the flange, and to heat the binder to render the adhesive tacky or adherent to the upper. The end rubbers are then actuated to rub the two ends of the binder rearwardly to tighten it and to make it stick firmly to the upper.

If desired, the end rubbers only might be heated and to such a degree that by being merely rubbed once over the end portions of the binder without standing in contact therewith they would cause it to adhere to the upper and become anchored while the unheated wipers held the body portion of the binder in binding relation to the upper about the toe. Advantageous results will, however, be obtained by heating the wipers to an extent to cause them to heat the surface of the upper engaged by them and to adapt them to soften an adhesive coated binder to cause it to stick to the upper for holding it in lasted position. Preferably the wipers are so heated that not only do they act more effectively than cold wipers for surface smoothing the upper and for molding it to the desired shape of the last and the innersole, but they are heated to a degree sufficient for shrinking the upper materials to the last. The upper does not require to be bound with the same security after having been overworked, molded and shrunk by the use of heated wipers. When heated wipers are used they will preferably be partially backed off to allow the binder adhesive to set while they hold the upper, the heel seat lasting being conveniently carried on during this time. I have shown the parts of the apparatus as operated by hand but the wipers and end rubbers may be actuated in proper time relation automatically and the binder may be placed automatically when the wipers are backed off to receive it, with or without previously warming the binder to render the adhesive sticky before the binder is placed. An apparatus embodying this feature will be separately claimed in another application.

The advantage which is obtained from the use of heated wipers in shrinking the fringe of the upper after it has been folded in over

the edge of the last bottom is of special importance. The shrinking of this overlaid portion of the upper at this time not only leaves the shoe of better shape around the toe so that the welt may set snugly when attached but also the inturned upper, by reason of its contraction or shrinking, has less tendency to slack back over the edge of the shoe when the wipers are withdrawn. If the heated wipers are allowed to remain over the upper long enough light upper material in some classes of work becomes so permanently formed that the shoe can be welted without binding in the toe.

15. While I have described a preferred use of this invention, it is obvious that the apparatus may be used with or without heat and may be employed simply for lasting purposes without regard to the means employed 20 for securing the upper. An adhesive coated toe binder which required simply to be moistened has been used with good results without heat and a binder, the adhesive of which is of proper quality, can be made to stick 25 satisfactorily by pressure without the application of heat or moisture.

Having explained the nature of the present invention, I claim as new and desire to secure by Letters Patent of the United 30 States:—

1. A machine of the class described having, in combination, toe end embracing wipers and means to actuate the wipers to work an upper over the margin of a 35 last into position to be bound and having provision for heating an adhesive coated binder to cause it to stick to the overworked upper while the wipers continue to hold the upper in position to be bound.

40. 2. A machine of the class described having, in combination, toe end embracing wipers, means to actuate the wipers to work an upper over the margin of a last into position to be bound, and means for heating 45 the wipers to cause them to heat the surface of the upper engaged by them and adapt them to soften an adhesive coated binder to cause it to stick to the upper for holding it in lasted position.

50. 3. A machine of the class described having, in combination, toe end embracing wipers, means to actuate the wipers to work an upper over the margin of a last into position to be bound, and devices arranged to 55 have a rubbing movement along the shoe in the rear of the wipers independently of the wipers and means to actuate them in the direction to tension a binder applied to the overworked upper.

60. 4. A machine of the class described having, in combination, toe end embracing wipers, means to actuate the wipers to work an upper over the margin of a last into position to be bound and heated devices arranged to engage the adhesive coated end

portions of a binder in the rear of the wipers to soften the adhesive and anchor the binder ends to the shoe.

5. A machine of the class described having, in combination, toe end embracing wipers, means to actuate the wipers to work an upper over the margin of a last into position to be bound, and binder rubbers arranged to engage the adhesive coated end portions of a binder in the rear of the wipers, means to heat said rubbers to soften the adhesive, and means to actuate them to wipe the end portions of the binder in the direction to tension it.

6. A machine of the class described having, in combination, toe end embracing wipers, means to actuate the wipers to work an upper over the margin of a last into position to be bound against the shoulder of the inner sole, and yielding devices moved with the wipers into operative relation to the shoe immediately back of the wiper ends and arranged for actuation separately from the wipers to press the upper against the shoulder in the rear of the wiper ends.

7. A machine of the class described having, in combination, toe end embracing wipers, means to actuate the wipers to work an upper over the margin of a last into position to be bound, a block mounted for movement with each wiper into operative relation to the side of the shoe, a yielding member eccentrically mounted on the block, and means for actuating the block to cause said yielding member to crease the upper against the innersole lip at the rear end of the adjacent wiper.

8. A machine of the class described having, in combination, toe end embracing wipers, means to actuate the wipers to work an upper over the margin of a last into position to be secured, and auxiliary lasting devices movable with the wipers into proximity to the side of the shoe at the rear of the wipers, and means in addition to the wiper operating means for actuating said auxiliary devices to force the upper over the shoe bottom.

9. A machine of the class described having, in combination, toe end embracing wipers, means to actuate the wipers to work an upper over the margin of a last into position to be bound against the shoulder of an innersole and to back the wipers away from the shoulder to permit the application of a binder, and manually operated means to engage the binder ends to tighten the binder while the wipers are so backed away.

10. A machine of the class described having, in combination, toe end embracing wipers, means to actuate the wipers to work an upper over the margin of a last into position to be bound against the shoulder of an innersole and to back the wipers away from the shoulder to permit the application of a

- 5 binder, and yielding means positioned by the wiper actuating means in proximity to the sides of the shoe and mounted for movement in engagement with the binder ends in the direction to tighten the binder while the wipers are backed away and for further movement with the wipers to take up any slack developed by the wipers when they are again advanced.
- 10 11. A machine of the class described having, in combination, end lasting wipers, end rubbers, and means to actuate said wipers to wipe the upper inwardly over the margin of a shouldered innersole in directions substantially perpendicular to the last edge and for actuating said end rubbers to crease the upper against said shoulder by movement in a direction lengthwise of said edge.
- 15 12. A machine of the class described having, in combination, end lasting wipers, end rubbers, and means to actuate said wipers to wipe the upper inwardly over the margin of a shouldered innersole in directions substantially perpendicular to the last edge and for actuating said end rubbers to advance their acting edges inwardly faster than the edges of the wipers whereby to draw the upper more than the upper acted on by the wipers.
- 20 13. A machine of the class described having, in combination, end lasting wipers, end rubbers, means to actuate said wipers to wipe the upper inwardly over the margin of a shouldered innersole in directions substantially perpendicular to the last edge and for actuating said end rubbers to crease the upper against said shoulder by movement in a direction lengthwise of said edge, and means for separately actuating the end rubbers.
- 25 14. A machine of the class described having, in combination, end lasting wipers for working an upper over the toe of a last, means for actuating the wipers forwardly and inwardly, devices movable with the wipers, and means for effecting a movement of said devices relatively to the wipers to form the upper adjacent to the tip seam into lasted position.
- 30 15. A machine of the class described having, in combination, end lasting wipers for working an upper over the toe of a last, means for actuating the wipers forwardly and inwardly, auxiliary lasting devices arranged at the ends of the toe wipers and positioned thereby relatively to the shoe, and means for actuating said auxiliary devices to crease the bulky upper materials adjacent to the tip seam into lasted position.
- 35 16. A machine of the class described having, in combination, end lasting wipers for working an upper over the toe of a last, means for actuating the wipers forwardly and inwardly, auxiliary lasting devices arranged at the ends of the toe wipers and positioned thereby relatively to the shoe, and
- 40 means by which said auxiliary devices may be actuated repeatedly to form the bulky upper materials adjacent to the tip seam into lasted position while the wipers continue to hold the upper that is engaged by them.
- 45 17. A machine of the class described having, in combination, end lasting wipers for working an upper over the toe of a last, means for actuating the wipers forwardly and inwardly, auxiliary lasting devices arranged at the ends of the toe wipers and positioned thereby relatively to the shoe, and means by which said auxiliary devices may be actuated to rub the upper lengthwise of the shoe for creasing into lasted position the bulky materials at the sides of the toe of a welt shoe.
- 50 18. A machine of the class described having, in combination, end lasting wipers for working an upper over the toe of a last, means for actuating the wipers forwardly and inwardly, auxiliary lasting devices arranged to engage the sides of the toe in advance of the wiper ends, and means for turning said devices with their peripheries in rubbing contact with the upper on the shoe bottom to crease it against the shoulder of the innersole.
- 55 19. A machine of the class described having, in combination, end lasting wipers, and rotatable auxiliary lasting devices having yielding peripheral upper creasing members arranged to overlie the shoe bottom at the ends of the wipers and means for turning said devices to crease the upper against the shoulder of the innersole.
- 60 20. A machine of the class described having, in combination, end lasting wipers, auxiliary lasting devices arranged to engage the upper yieldingly at the ends of the wipers, and means for actuating said wipers forwardly and inwardly and for actuating said devices inwardly faster than the wipers.
- 65 21. A machine of the class described having, in combination, end lasting wipers, auxiliary lasting devices arranged to engage the upper yieldingly at the ends of the wipers, and means for actuating said wipers forwardly and inwardly and for actuating said devices inwardly with the wipers, said machine having provision for additionally actuating said devices.
- 70 22. A machine of the class described having, in combination, the end wipers 6, means for actuating the wipers, the auxiliary lasting devices 21 operatively connected with said actuating means and movable with the wipers, and means for actuating said devices.
- 75 23. A machine of the class described having, in combination, the end wipers 6, means for actuating the wipers, the auxiliary lasting devices 21 movable with the wipers, and means for actuating said devices with the wipers and for additionally actuating them.
- 80 85 90 95 100 105 110 115 120 125 130

24. A machine of the class described having, in combination, the end wipers 6, means for actuating the wipers, the auxiliary lasting devices 21 movable with the wipers and mounted to turn, said devices having eccentric work-engaging members 21, and means for turning said work-engaging members to crowd the upper against the shoulder of the innersole.
- 10 25. A machine of the class described having, in combination, end lasting wipers, auxiliary lasting devices, and connected means for actuating said wipers and devices together including means by which said auxiliary lasting devices may be actuated separately.
- 20 26. A machine of the class described having, in combination, end lasting wipers, auxiliary lasting devices, and connected means by which said auxiliary devices may be moved with the wipers and simultaneously given an additional movement.
- 25 27. A machine of the class described having, in combination, end lasting wipers, auxiliary lasting devices, and connected means by which said auxiliary devices may be moved with the wipers and simultaneously given an additional movement, said means including provision for allowing the additional movement of the auxiliary devices to be continued after the wipers have stopped.
- 30 28. A machine of the class described having, in combination, end lasting wipers, auxiliary lasting devices, levers 15, 22 connected to said wipers and devices respectively and having a common operating handle and provision for adjustment of the wipers and devices into different relative positions.
- 35 29. A machine of the class described having, in combination, end embracing wipers, operating mechanism for the wipers, and
- heating means for the wipers all organized to work an upper into lasted position over 45 the margin of the end portion of a last and permanently to shrink the overlasted upper on a curved line extending along said margin of the end portion of the last bottom.
- 50 30. A machine of the class described having, in combination, upper shrinking means formed and arranged to engage the overlasted upper upon the bottom of the end portion of a last, means for heating said means to an extent sufficient to shrink the upper permanently, and means to operate said first-mentioned means to shrink the overlasted upper for the purpose described upon a curved line extending around the 60 end of the last and located between the edge of the last bottom and the edge of the upper.
31. A machine of the class described having, in combination, upper shrinking means 65 formed and arranged to engage the overlasted upper upon the bottom of the end portion of a last, means for heating said means to an extent sufficient to shrink the upper permanently, and operating mechanism 70 to advance said shrinking means in wiping contact with the upper on lines to gather it inwardly over the feather and against the lip of a welt shoe innersole and to depress the shrinking means upon the 75 gathered upper and hold the upper until it is permanently shrunk in the position to which it has been forced by the movement of the shrinking means.
- In testimony whereof I have signed my 80 name to this specification in the presence of two subscribing witnesses.
